UNITED STATES PATENT OFFICE.

JAMES BOORMAN STRONG, OF HILLBURN, NEW YORK,

DESIGN FOR A CABLE-RACK HANGER.

45,918.

Specification for Design.

Patented June 9, 1914.

Application filed December 24, 1913. Serial No. 808,624. Term of patent 14 years.

To all whom it may concern:

Be it known that I, JAMES BOORMAN STRONG, a citizen of the United States, and a resident of Hillburn, county of Rockland, State of New York, have invented a new, original, and ornamental Design for Cable-Rack Hangers, of which the following is a specification, reference being had to the accompanying drawing, forming a part thereof.

In the drawings: Figure 1 represents a

side elevation of a cable rack hanger embodying my new design; and Fig. 2 represents a bottom elevation.

I claim:

The ornamental design for a cable rack hanger, as shown.

JAMES BOORMAN STRONG.
